UNITED STATES PATENT OFFICE.

FREDERICK ROBT. SEIDENSTICKER, OF WEST MERIDEN, CONNECTICUT, AS-SIGNOR TO BRADLEY & HUBBARD, OF SAME PLACE.

DESIGN FOR CHANDELIER.

Specification forming part of Design No. 5,343, dated October 31, 1871.

To all whom it may concern:

Be it known that I, FREDERICK ROBT. SEIDENSTICKER, of West Meriden, in the county of New Haven and State of Connecticut, have invented a new Design for Chandelier; and I do hereby declare the following, when taken in connection with the accompanying photographic illustration, to be a full, clear, and exact description of the same, and which said illustration constitutes part of this specification and represents a perspective view of the chandelier complete.

This invention relates to a design for chandelier for either gas or kerosene-burners—here represented as kerosene; and consists in the peculiar configuration of the arm or bracket, as shown in the accompanying illustration, whether in connection with the center or not.

From the center several brackets extend of the form or shape shown in the accompanying illustration. Starting from the body of the chandelier the bracket curves upward; thence turning

outward in a horizontal line; thence down in a straight line inclining, outward, to the lowest point; thence turning outward in a horizontal line, upon the end of which last-named portion the head or base of the burner is applied, the center being of a form corresponding to the general style of the bracket.

As is usually the case in chandeliers these brackets may be used without the center, as for wall-brackets; I therefore do not wish to be understood as confining my design to the combination of the brackets and center, but to the brackets with or without the center.

I claim as my invention—

The design for chandelier, as shown in the accompanying photographic illustration.

F. ROBT. SEIDENSTICKER.
